UNITED STATES PATENT OFFICE.

BURLEIGH F. ANNIS, OF CHATTANOOGA, TENNESSEE.

DAMPER.

1,419,438.

Specification of Letters Patent. Patented June 13, 1922.

Application filed October 21, 1921. Serial No. 509,241.

To all whom it may concern:

Be it known that I, BURLEIGH F. ANNIS, a citizen of the United States of America, residing at Chattanooga, in the county of 5 Hamilton and State of Tennessee, have invented certain new and useful improvements in Dampers; and I do hereby declare that the following is a full, clear, concise, and exact description of the same, such as will 10 enable others skilled in the art to which it appertains to make and use the same.

This invention relates to improvements in fire places or the so termed dome dampers, having for an object to provide a dome 15 damper embracing a novel construction and arrangement of operating mechanism therefor, whereby the damper may be caused to move to various positions with respect to the dome to increase or decrease the draught in 20 the fire place as may be desired, such mechanism being arranged so that access may be had thereto from within the fire place and in addition, the different parts thereof confined within the dome can be readily repaired, 25 replaced or adjusted with respect to each other without the necessity of removing the same from the compartment provided therefor within said dome.

It is also an object of the invention to provide 30 a damper operating mechanism within the dome in a position whereat although it is within the dome, it will not be subjected to intense heat given off by the heated products of combustion passing from the fire- 35 place through the damper opening in the dome into the chimney flue, thus eliminating rapid deterioration of such operating mechanism, as in the case of those operating means of similar devices which are arranged with- 40 in their respective domes but in the direct path of outlet for the heated products of combustion through the damper opening upon movement of the damper to an open or partially open position.

45 Other objects will be in part obvious and in part pointed out hereinafter.

In order that the invention and its mode of operation may be readily understood by persons skilled in the art, I have in the accompanying 50 illustrative drawing, and in the detailed following description based thereon set out one possible embodiment of the same.

In these drawings:—

Figure 1 is a top plan view of the improved damper;

Figure 2 is a vertical longitudinal section therethrough;

Figure 3 is a vertical transverse section through the same;

Figure 4 is an enlarged fragmentary detail in section showing the arrangement of the operating mechanism; and,

Figure 5 is a fragmentary detail in elevation showing the connection between the compartment closure and the compartment.

Having more particular reference to the drawing, it will be noted that I have shown my improved damper, for purposes of illustration, as arranged in position within a chimney of a fire place indicated generally 70 by the numeral 1; the dome 2 of the device being formed with lateral marginal flanges 2' which are adapted to be engaged with and supported upon said chimney 1. The dome is provided with a substantially rectangular shaped opening in the top thereof which, as will be understood, affords the necessary passage for creation of draught through the chimney 1 from the fire place arranged there below.

80 A damper or door 3 is provided in the opening and has bearing pintles 4 formed upon and extending laterally from the intermediate portions of the opposite ends thereof, said pintles being journalled in 85 suitable bearings 5 formed in the adjacent portions of the opposite end walls of the dome 2; one of said pintles being formed with an extension allowing the same to be arranged at a point beyond its respective 90 bearing, for a purpose which will be subsequently described.

Formed in one end wall of the dome 2 and preferably cast integral therewith is an inwardly opening pocket or compartment 95 6, which, as will be noted, is so positioned with respect to the damper opening in the upper portion of the dome 2 as to be laterally offset therefrom and to receive the extended bearing pintle 4 of the damper 100 door 3 therein. The upper portion of this compartment 6 is open and to close the same, a cover plate 7 is provided, said cover plate consisting, preferably, of a cast body formed with tapering sides and having a 105 laterally disposed apertured ear 8 formed adjacent one end thereof, whereby to permit of the connecting of said plate through the medium of a bolt 9, to an adjacent portion of the dome 2. In order to prevent 110

swinging movement of the plate 7 about the bolt 9, I may and preferably do form a recess 10 in the free end of said plate, whereby the same may be engaged over a 5 lug 11 arranged upon the upper marginal portion of the adjacent end wall of the compartment 6. Thus, it will be understood that with tightening of the bolt 9, the cover plate 7 will have connection with 10 the dome and with that wall of the compartment 6 opposite to said connection with the dome.

With a view towards providing operating mechanism for the damper door, an 15 operating rod 12, preferably square in cross section is passed through bearing openings, one of which is formed in the front wall of the compartment 6 while the other is formed in the rear wall of the dome 2, a 20 bearing sleeve 13 adapted to be received in the wall or chimney breast provided with the damper whereby to provide effectual support for the outer extremity of the rod 12, while a handle 14 is secured to the 25 outer end thereof to facilitate rotation of the same. Previous to the engaging of the inner end of the operating rod 12 in the bearing opening in the rear wall of the dome 2, a worm gear 15 is engaged over 30 that portion of the rod within the lower part of the compartment 6 and is secured in adjusted position upon said rod through the medium of set screw 16 engaging a split bracket. This worm gear 15 is adapted to 35 mesh with a segmental gear 17 fixedly mounted upon the end of the extended bearing pintle 5 within the compartment 6. Thus, it will be understood that with rotation of the rod 12, pivotal movement of 40 the damper door 3 with respect to the opening therefor in the upper portion of the door 2 will be effected and by consequence, said damper may be adjusted to various positions with relation to said opening for 45 increasing or decreasing the draught to meet with the requirements or desires of a user.

It, of course, will be understood that the 50 assembly of the operating mechanism consisting of the rod 12, the worm gear 15 and the segmental gear 17 will be materially facilitated by the removal of the cover plate 7 from over the upper end of the compartment 6. With such assembly, however, the 55 cover plate 7 may be replaced and locked in position over the open upper end of said compartment through the medium of the bolt 9 and the engagement of the recess 10 in said plate over the lug 11 on the forward end wall of the compartment 6.

From the foregoing, it is believed that the 60 operation of my improved device will be fully understood; the rod 12 being rotated by engaging the handle 14 to effect pivotal movement and adjustment of the damper 3

with relation to the opening therefor in the dome 2 through medium of the worm gear arranged in the compartment 6.

Due to the peculiar arrangement of the operating mechanism with relation to the 70 damper receiving opening in the top of the dome 2, it will be understood that such mechanism will not be in the direct path of travel taken by the heated products of combustion as they are exhausted from the fire place and 75 discharged into the chimney flue for ultimate delivery to the atmosphere. Hence, it necessarily follows that the operating mechanism consisting of that portion of the rod 12 within the compartment 6, the worm gear 80 15 and the segmental gear 17 will not be heated to that intense degree as they would be should they be arranged within the direct path of travel of the heated products of combustion passing from the fire place 85 through the damper opening into the chimney. Because of this arrangement, rapid deterioration of the operating mechanism will be eliminated and further, frequent adjustments of the same, such as would be 90 necessitated by reason of expansion and contraction of the various parts thereof when subjected to different degrees of heat will be avoided. Also, it is to be understood that due to the specific formation of the pocket or 95 compartment 6 with its open upper end, that minor adjustments of the operating mechanism within the same or repairing or replacing thereof may be effected with but little effort and further, when desired, may be 100 cleaned. Also, it will be understood that access may be had to the operating mechanism from within the dome damper by way of the fire place, although to effect adjustments of the mechanism, the removal of the 105 cover plate 6 is preferable.

Manifestly, the construction shown is capable of considerable modification and such modification as is within the scope of my claims, I consider within the spirit of my 110 invention.

I claim:

1. A fire place damper including a dome, having an integral inwardly opening closed top compartment in one side thereof off-set 115 laterally from the damper opening and accessible from within the same, a damper in said opening having pivotal mounting in the side walls of the dome, one of the pivotal bearings of said damper being elongated and 120 extending into the laterally off-set compartment, and damper operating mechanism within said compartment for imparting rotary movement to the damper.

2. A fire place damper including a dome 125 having an integral inwardly opening closed top compartment in one side thereof and a damper opening in the top of the dome, said compartment being arranged out of the direct line of draught through said damper 130

opening but accessible from within the same, a damper in the opening having pivotal mounting in the side walls of the dome, one of the pivotal mountings being elongated 5 and extended into said compartment, and means in the compartment connected to said damper for imparting pivotal movement thereto.

3. A fire place damper including a dome 10 having an integral inwardly opening compartment in one side thereof off-set laterally from the damper opening but accessible from within the same, the top of said compartment being open, means for closing said 15 open top of the compartment, a damper in the opening in the dome having pivotal mounting in the side walls thereof, one of the pivotal bearings of said damper being elongated and extending into the laterally 20 off set compartment and damper operating mechanism within said compartment con-

nected to said damper for imparting pivotal movement thereto.

4. A fire place damper including a dome having the top thereof open and an integral 25 inwardly opening compartment in one side wall thereof off-set laterally from said open top but accessible from within the dome, a damper received in the open top having bearing pintles upon its opposite ends pivotally 30 engaging the opposite end walls of said dome, one of said bearing pintles being elongated and extended into the laterally off-set compartment, the upper end of said laterally off-set compartment being open, a removable 35 plate for covering said open end of the compartment, and a damper operating mechanism within the compartment connected to said extended bearing pintle.

In witness whereof I have hereunto set my 40 hand.

BURLEIGH F. ANNIS.
